DESIGN FOR A GARMENT BUTTON

Otto J. Lavaty, Chicago, Ill.

Application June 18, 1947, Serial No. 139,791

Term of patent 14 years

(Cl. D17—2)

To all whom it may concern:

Be it known that I, Otto J. Lavaty, a citizen of the United States, and a resident of the city of Chicago, county of Cook, and State of Illinois, have invented a new, original, and ornamental Design for a Garment Button, of which the following is a specification, reference being had to the accompanying drawing, forming a part thereof, in which

My design for a garment button is characterized by the large bead surrounding the outer edge in combination with the convex sides, one of which is slightly flattened where the eyelet is attached thereto, all as illustrated on the drawing.

I claim:

The ornamental design for a garment button, as shown and described.

OTTO J. LAVATY.
